UNITED STATES PATENT OFFICE.

GEORGE E. WATSON, OF BANNACK CITY, MONTANA TERRITORY.

DESIGN FOR A SLEIGH.

SPECIFICATION forming part of Design No. 14,109, dated July 17, 1883.

Application filed May 14, 1883. Term of patent 7 years.

To all whom it may concern:

Be it known that I, GEORGE E. WATSON, of Bannack City, in the county of Beaver Head and Territory of Montana, have invented and produced a new and original Design for Sleighs, of which the following is a full, clear, and exact description.

Reference is to be had to the accompanying drawing, forming part of this specification, in which the figure is a side elevation of my newly-designed sleigh.

The essential feature of my design for sleighs consists of the margins of the surfaces of the runners *a*, sides *b*, goose-neck *c*, and top *d*, figured with the scalloped borders *f*, which is to be done, in practice, with red colors on a white ground; or it may be white color for the borders and red for the ground; or other materially differing and thereby contrasting colors may be used.

My design for the body of the sleigh also consists of scalloped borders *g* on the margin of the sides and back of the body *h*, and on the front and top of the dash-board, also colored in strong contrast with the ground—for instance, white borders and red ground.

My design for a sleigh also consists of the sides of the runner part, formed with the

heart-shaped opening *k*, also with the oval opening *l*, also with the ogee form of the rear end at *n o*, and also with the notch *p* between the top *d* and the goose-neck *c*.

I claim—

1. The design for the runners, sides, tops, and goose-necks of a sleigh, consisting of 35 scalloped borders *f* on the margins of said parts, as shown.

2. The design for the sides and back of the body and the dash-board of a sleigh, consisting of the scalloped borders *g*, as shown. 40

3. The design for a sleigh, consisting of the sides of the running part, formed with the heart-shaped opening *k* and the oval opening *l*, as shown.

4. The design for a sleigh, consisting of the 45 sides of the running part, formed with ogee from *n o* of the rear end, as shown.

5. The design for a sleigh, consisting of the sides of the running part, formed with the notch *p* between the top *d* and the goose-neck 50 *c*, as shown.

GEORGE EDWARD WATSON.
